United States Patent Office

Des. 177,904
Patented June 5, 1956

177,904

RACK

Maurice Duchin, New York, N. Y.

Application March 16, 1955, Serial No. 35,065

Term of patent 7 years

(Cl. D33—3)

FIG. 2.

FIG. 3.

Figure 1 is a front elevational view of a rack, showing my new design;

Figure 2 is a side elevational view thereof; and
Figure 3 is a top plan view of the same.

I claim:

The ornamental design for a rack, as shown.
